UNITED STATES PATENT OFFICE.

DAVID MURRAY AND THOMAS W. McGREGOR, OF RUSHFORD, MINNESOTA.

BARREL-MAKING MACHINE.

SPECIFICATION forming part of Letters Patent No. 232,054, dated September 7, 1880.

Application filed November 20, 1879.

To all whom it may concern:

Be it known that we, DAVID MURRAY and THOMAS W. McGREGOR, of Rushford, in the county of Fillmore and State of Minnesota, 5 have invented a new and Improved Barrel-Machine, of which the following is a specification.

The object of our invention is to provide in a single machine the several mechanisms and 10 devices for trussing and working the ends of barrels, kegs, &c., preparatory to receiving the heads.

The invention consists in the construction and combination of parts, as hereinafter described and claimed.

In the accompanying drawings, Figure 1 is a plan of our improved barrel-machine. Fig. 2 is a vertical longitudinal section of the machine, taken on line $x-x$ of Fig. 1. Fig. 3 is a 20 cross-section taken on line $y-y$ of Figs. 1 and 2. Fig. 4 is a cross-section taken on line $y'-y'$ of Fig. 2. Fig. 5 is a sectional front elevation of one of the face-plates and part of the trussing mechanism. Fig. 6 is a vertical longitudinal 25 section of the face-plate and trussing mechanism, taken on line $z-z$ of Fig. 5; and Fig. 7 is a detail of the devices for operating the movable knives of the face-plates.

Similar letters of reference indicate corresponding parts.

Referring to the drawings, A is the frame of the machine. B is the main driving shaft, carrying the pulley a on one end, which is to be belted to the driving-pulley of the power 35 which operates the machine.

Inside of the frame, on shaft B, are pulleys b b' , held in connection with the shaft by feathers b^2 , which turn with said shaft, but are adapted to move back and forth to and from 40 each other. Beyond pulley b' a pinion, c , is placed loosely on shaft B. On the back of pinion c is an annular conoidal flange, c' . At the end of shaft B another loose pinion, d , is placed on said shaft, which is likewise provided with an annular conoidal flange, d' , facing flange c' .

Between pinions c d are placed on shaft B double-conical friction-clutch plugs CC' , joined by a neck, c^2 , which slide back and forth on feather e , so that they can be made to engage flanges c' or d' at will, for the purpose of communicating the motion of shaft B to pinions c

d , or to occupy a midway position between said flanges and throw the pinions out of gear and allow shaft B to rotate independently of 55 said pinions.

In the upper part of the frame A are fixed two shafts, D D' , parallel to each other. Shafts D D' are each provided with right and left screw-threads e' e^2 . On screw-threads e' 60 are burrs f , and on threads e^2 are similar burrs f' . Between burrs f is held a ring, E, and between burrs f' is held a second ring, E' . Rings E E' form the ends of the trussing mechanism. Arms g g' project from rings E E' on each side within shafts D D' , and to the arms g g' are fastened the ends of the semi-elliptical dovetailed grooved guides g^2 g^3 . In guides g^2 g^3 , respectively, are held by a dove-tailed joint the segments h h' , which are coupled 70 together in pairs by pins h^2 .

The segments are rigidly connected by rods h^3 , attached to pins h^2 , with the bar h^4 , which lies on top of shaft B, and is held on top of said shaft by a U-shaped guide, h^5 , extending 75 down on each side of said shaft.

The ends i i' of bar h^4 are turned up at right angles and provided with teeth i' , which are engaged by the ratchet-wheels i^2 on shafts i^3 . Shafts i^3 carry grooved pulleys j . Around said 80 pulleys are run cords j' . One end of each of said cords is attached to a spring, i^2 , while the opposite ends are attached to a foot-treadle, E^2 . By pressing on treadle E^2 the cords j' are caused to rotate pulleys j and shafts i^3 , and the 85 ratchet-wheels i^2 , engaging teeth i' , raise the bar h^4 , and the rods h^3 throw the segments h h' up in the direction of arrows 1, Fig. 5. On releasing the treadle E^2 the springs j^2 , acting on the several parts mentioned in a reverse direction, draw the segments h h' down to the position segments h are shown to occupy in Fig. 5.

The function of the segments h h' is to truss or force the hoops onto the barrel. The segments are made detachable from the guides to allow substitution of others of different curvature—that is to say, of a curvature corresponding to the barrel being trussed, &c.

The barrels are centered by and supported 100 upon a rest, j^3 , Figs. 2 and 6, which consists of a curved bar having a suitable fixed support.

Within the rings E E' , respectively, are se-

cured beveled rings $E^3 E^4$, which serve as means for forcing the end hoops on the barrel. The rings $E^3 E^4$ are held by clamp-screws, and thus adapted for being conveniently detached, 5 when required, for the purpose of substituting other rings of less diameter for use in trussing smaller barrels.

Back of rings $E E'$, respectively, are cross-heads $k k'$, supported and sliding freely on 10 shafts $D D'$. Cross-heads k are connected together by rods k^2 , the ends whereof are hooked to burrs f , and cross-heads k' are connected by similar rods k^3 , hooked to burrs f' .

In cross-heads k is journaled a shaft, F , and 15 in cross-heads k' is journaled a similar shaft, F' . Shaft F carries a pulley, l , which is belted to pulley b and a circular face-plate, F^2 , close to ring E . Shaft F' carries a pulley, l' , which is belted to pulley b' and a face-plate, F^3 close 20 up to ring E' . In face-plates F^2 and F^3 are radial slats $l^2 l^3 l^4$, in which are confined, by dovetailed joints, plates $m m' m^2$, respectively, and to said plates are fixed heads $m^3 m^4 m^5$. In head m^3 is fixed the chamfering-knife n . 25 In m^4 is the evening-knife n' , and in m^5 is the crozing-knife n^2 . All of these knives are attached to the said heads with their points projecting out between the heads and the beveled rings $E^3 E^4$. At right angles to the edge 30 of the chamfering-knife n an edging-knife, n^5 , is passed through an opening, n^6 , in the face-plates $F^2 F^3$, so that its cutting-edge forms a right-angular continuation of the edge of the chamfering-knife. The purpose of knife n^5 is 35 to trim off the ends of the staves, and thus level the ends of the barrels, &c.

On the backs of each of the plates $m' m^2$, with which the evening-knife n' and crozing-knife n^2 are connected, is a rack, o , projecting 40 into an opening, o' , extending entirely through the face-plates. Racks o mesh with spur-wheels o^2 , pivoted in ears extending from the face-plate on each side of the openings o' . Spur-wheels o^2 also mesh with racks o^3 on 45 sleeves $G G'$. Said sleeves are placed on shafts $F F'$ and extend over the hubs or sleeves of the face-plates, and they have a free sliding movement, which is limited in the direction of the face-plates by the ends of the hubs, and 50 in the opposite direction by collars p , placed on the shafts. The sleeves $G G'$, being connected with the shafts $F F'$ by a feather, are rotated with said shafts.

The purpose of the sleeves $G G'$, racks $o o^3$, 55 and spur-wheel o^2 is to throw the evening-knife n' and crozing-knife n^2 up in the direction of the arrows 2, and thus bring them in contact with the inside of the ends of the barrels after the chamfering and leveling is completed, and also to move them back while the 60 chamfering and leveling is being done. The movements that adjust the said knives are produced by the sleeves $G G'$ in the following manner: When the sleeves $G G'$ are moved in 65 the direction of arrows 3 the racks o^3 turn the spur-wheels o^2 in the direction of arrow 4, and said spur-wheels o^2 throw the racks o , and

with them plates $m' m^2$ and knives $n' n^2$, in the direction of arrows 2. When the sleeves $G G'$ are moved back in the opposite direction from 70 arrow 3 the movements of the several recited parts are reversed and the plates $m' m^2$ and knives $n' n^2$ are thrown in an opposite direction from that indicated by arrows 2. The backward movements of sleeves $G G'$ are produced automatically by springs p' , wrapped 75 around shafts $F F'$, between the parts of the sleeves on the said shafts and the ends of the hubs of the face-plates, in the manner clearly shown in Figs. 2 and 6. The forward movements of sleeves $G G'$ are produced by levers $H H'$, having forked ends p^2 , which are loosely connected with the respective sleeves. The power ends of said levers $H H'$ are held respectively in the forked ends of rods p^3 , (see 85 Fig. 7,) which have their opposite ends pivoted to a plate, I , on opposite sides of the center of said plate, so that when said plate is turned on its axis the rods p^3 will move in opposite directions. The plate I is provided with 90 an arm, q , which is pivoted to one end of a rod, q' , the opposite end whereof is pivoted to the weight end of a lever, I' . When lever I' is thrown up in the direction of arrow 5, through rod q' , plate I , and rods p^3 , levers $H H'$ are 95 moved in the direction of arrows 6, and these movements of said levers throw the sleeves $G G'$ in the direction of arrows 3, with the resulting effect of moving the evening and crozing knives out in the direction of arrows 2. As 100 soon as the lever I' is relieved from pressure the springs p' reverse the movements of lever $H H'$ and all connected parts.

As before stated, the shaft B moves independently of spur-wheels $c d$, and this independent movement is communicated through pulleys $b b'$ by belts to the pulleys $l l'$, shafts $F F'$, and face-plates $F^2 F^3$, so that said face-plates have an independent rotary movement. At the same time said face-plates, together 110 with the cross-heads $k k'$, rings $E^3 E^4$, and pulleys $l l'$, have a reciprocating movement which is communicated to them in the following manner: Pinion c gears with an idle-wheel, J , which, in turn, gears with spur-wheels $J' J''$, 115 fixed respectively to shafts $D D'$. When shaft B rotates to the right, if the pinion c is engaged by the clutch, it communicates motion through the idle-wheel J to spur-wheels $J' J''$, which are thereby turned in the direction of 120 arrows 7, and the same motion is given to shafts $D D'$. This causes the right screw-threads e'' to throw the burrs f' and attached parts in the direction of arrow 8, and the left screw-threads e' to throw burrs f and attached 125 parts in the direction of arrow 9. To reverse this movement without changing the motion of the main shaft B a spur-wheel, K , is fixed to shaft D , which meshes with the pinion d , so that by throwing pinion d into connection 130 with shaft B through the clutch the spur-wheel K , shaft D , and (through the spur-wheel J' , idle-wheel J , and spur-wheel J'') shaft D' are rotated in the direction of arrow 10, whereby

the movements of burrs $f f'$ are reversed, and the rings $E E'$, face-plates $F^1 F^2$, and connected parts are moved from each other in a direction opposite to that indicated by arrows 5 8 9, Fig. 2.

The reverse movements are brought about by the clutch, composed of annular flanges $c' d'$ and conical plugs $C C'$. The conical plugs are moved by a lever, L , provided with a yoke, 10 r , which incloses and is pivoted to a collar, r' , held in an annular groove in the neck c^2 , that connects the two plugs $C C'$. The said plugs, being feathered to shaft B, turn with said shaft and within the collar r' . By throwing plug 15 C into connection with flange c' the pinion c is caused to rotate with said plug, and by throwing plug C' into connection with flange d' pinion d is caused to rotate, while pinion c' comes to a stop. By placing the plugs $C C'$ 20 out of connection with both flanges $c' d'$ both pinions $c d$ remain stationary.

For convenience in operating the machine the power end of lever L is connected by a rod, s , with a brake-lever, L' , the power end 25 whereof is held under a guard, s' , provided with a middle notch, s^2 , for holding the brake-lever L' , and through it to hold the plugs $C C'$ out of connection with the flanges $c' d'$. Lever L is also connected by a rod, t , with a stop- 30 lever, L^3 , the power end t' whereof extends up in the line of travel of the finger t'' , attached to the outside cross-head, k' , so that when said cross head is being moved backward on shafts $D D'$ the said backward movement is 35 stopped by the finger t'' striking the lever L^3 and moving said lever sufficiently to disconnect the clutch and stop the movement of pinions $c d$.

As the pulleys $l l'$ receive their motion from 40 pulleys $b b'$, it is necessary that the latter shall follow the movements of pulleys $l l'$ when carried backward and forward by the movement of the burrs $f f'$ on shafts $D D'$. For this purpose rods $u u'$ extend down from cross- 45 heads $k k'$, respectively, and yokes $v v'$ on said rods are placed in grooves $w w'$ in the hubs of

wheels $b b'$. As wheels $b b'$ are feathered to shaft B and slide freely back and forth on said shaft, the rods $u u'$ carry the pulleys $b b'$ back and forth with the cross-heads $k k'$, and thus 50 keep them in line with pulleys $l l'$.

Having thus described our invention, we claim as new and desire to secure by Letters Patent—

1. The combination of the curved rests j^3 55 with the rings placed vertically for receiving the ends of the barrel-staves, the curved segments $h h'$, and movable slotted guides $g^2 g^3$, said rests being supported and arranged horizontally contiguous to the lower portion of the 60 rings, as shown and described.

2. In combination with the evening-knives n' and crozing-knives n^2 , the sleeves $G G'$, sliding on main shaft, and spur-wheels and ratchets interposed between said sleeves and 65 the crozing and evening knives, in the manner and for the purpose substantially as described.

3. The combination, with the evening-knife n' and crozing-knife n^2 , attached respectively to plates $m' m^2$, racks o , and spur-wheels o^2 , 70 with sleeves $G G'$, having racks o^3 , the springs p' , rods p^3 , plate I , connecting-rod q' , and lever I' , substantially as and for the purpose specified.

4. In combination with segments $h h'$, guided 75 in ways $g^2 g^3$, the rods h^3 , bar h^4 , provided with a U-shaped guide, h^5 , and ratchet-teeth i' , the pinions i^2 , grooved wheels j , cords j' , springs j^2 , and treadle E^2 , as operative mechanism to work the segments, substantially as 80 described.

5. In combination with shafts $F F'$, carrying face-plates $F^2 F^3$, and pulleys $l l'$, respectively, the sliding pulleys $b b'$ on the main shaft B, connected with said pulleys $l l'$, substantially as described. 85
